SPRAYING DEVICE

Cecil Bishop Redman King, Talawakelle, Ceylon

Application May 17, 1935, Serial No. 21,987
In Great Britain April 10, 1934

2 Claims. (Cl. 299—140)

This invention relates to spraying devices such as are used for example in spraying insecticides and fungicides on to trees and the invention has for its object the provision of an efficient nozzle device for producing a finely divided spray.

The apparatus according to the invention comprises a nozzle or spraying head composed of a main body made of metal or other suitable material, and a separate member in the form of a nozzle proper which is detachably affixed to said main body. The main body is formed with an elongated passage or mixing chamber into the side of which are led ducts whereby said passage is placed in communication with pipe lines which supply thereto, respectively, an air current and stream of liquid under pressure. Outlet orifices, one or more in number are formed in an end wall of the main body and serve to deliver into the nozzle a mixture of air and liquid. The main body is fitted with an adjustable needle valve for controlling the flow of the liquid, and is provided also with a removable plug or cap at the end remote from the nozzle fitted end to enable the interior of the main body to be cleaned out easily and expeditiously.

A practical embodiment of the invention is illustrated in the accompanying drawing wherein:—

30 Figure 1 is a longitudinal section through the device, and

Figure 2 is a front end view thereof, with the nozzle proper removed.

Referring to the drawing the device comprises a main body 3 cast or otherwise made of metal and of elongated rectangular shape in plan and cross section, a tubular passage 4 which constitutes a mixing chamber being formed in said body at a central position to extend practically the full length thereof. Said passage 4 opens at the rear end of the body but is closed normally by a plug 5 screwed into the said end. In the front end wall 6 of the body a hole is formed on the axis of the aforesaid passage, said hole being threaded to receive the threaded clamping rod 7 of a nozzle fitting.

Said nozzle fitting comprises a tubular elbow 8 along one limb of which extends the clamping screw 7 which latter is adapted to project from the outer end of said limb, said projecting end having a head 9 adapted to bear upon the outer surface of the elbow and secure same in position. Said limb of the elbow engages into an annular groove 10 formed in the end wall of the body. The second limb of the elbow (which

is disposed at right angles to the axis of the passage in the main body) has a screw threaded extremity upon which is fitted an end cap 11 having formed therein a centrally positioned emission orifice 12 which may be outwardly flared.

In the lower part of the main body there are formed a pair of internally threaded sockets 13 adapted to receive the threaded ends of pipes 14 and 15 through which are supplied respectively, and under pressure, the liquid to be atomized, and air. An inlet orifice 16 formed in the base of each socket leads into the mixing chamber 4. Into the top of the main body is screwed a needle valve 17 having a conical extremity 18 which is adapted to pass into a conical mouth of the liquid inlet orifice to regulate the effective size thereof. Said needle 17 is provided with a lock-nut 19.

Passages 19 formed in the end of the main body allow the mixture to pass from the mixing chamber 4 into the nozzle proper 8.

It will be understood that the air admitted under pressure into the passage 4 in the main body, will encounter or impinge on the stream of liquid which also is fed into said passage under pressure, and will effect atomization, which latter is assisted by the restricted size of the liquid inlet orifice (controlled by the needle valve 17), the construction afforded by the orifices whereby the main body communicates with the nozzle, and the restricted size of the emission orifice of the nozzle. If necessary provision may be made for controlling the flow of air into the mixing chamber.

The spraying device constructed as above described is economical in use since it will produce an effective spray when using appreciably less liquid than a spraying device or power operated machine of conventional type. Thus, when used to spray insecticides and fungicides, these can be of greater strength without incurring additional expense.

I claim:

1. A spraying device comprising in combination an elongated main body, a bore formed in said body along its axis and terminating short of one end thereof, passages formed in the end wall remaining at one end of said body, an annular groove formed in the outer face of said end wall outside the boundary of the passages therein, an elbow having its inner end seating in said groove, a clamping screw positioned at the axis of the annular groove and engaging into said end wall, said screw serving as a holding

- means for the elbow and as an axial spindle about which the elbow is adapted to turn, an axially positioned outlet orifice on the outer end of the elbow for directing an emitted stream perpendicular to the principal axis of the device, valve-controlled liquid inlet and non-controlled air inlet passages formed in the main body and both leading into the bore therein which there-
5 by constitutes a mixing chamber, and a closure
10 plug for fitment in the open end of said bore.
2. A spraying device comprising in combination an elongated main body, a bore formed in said body along its axis and terminating short

of one end thereof to leave an end wall, an elbow having one limb rotatably mounted on the outer face of said end wall, passages in said end wall for establishing communication between the bore and the elbow, an outlet orifice on the outer end of the elbow for directing an emitted stream perpendicular to the principal axis of the device, valve-controlled liquid inlet and non-controlled air inlet passages formed in the main body and both leading into the bore therein which there-
5 by constitutes a mixing chamber, and a closure
10 plug for fitment in the open end of said bore.

CECIL BISHOP REDMAN KING.
